UNITED STATES PATENT OFFICE.

JOSEPH P. HASTY, OF SUPERIOR, NEBRASKA.

RAILWAY-SWITCH.

SPECIFICATION forming part of Letters Patent No. 717,991, dated January 6, 1903.

Application filed October 30, 1902. Serial No. 129,444. (No model.)

To all whom it may concern:

Be it known that I, JOSEPH P. HASTY, a citizen of the United States, residing at Superior, in the county of Nuckolls and State of Nebraska, have invented certain new and useful Improvements in Railway-Switches; and I do declare the following to be a full, clear, and exact description of the invention, such as will enable others skilled in the art to which it appertains to make and use the same.

My invention relates to an improvement in railway-switches, particularly with reference to the means for operating the switch-rails and for indicating the position thereof; and it 15 consists in the peculiar construction and combination of devices hereinafter fully described and claimed.

The object of my invention is to effect improvements whereby a single stand may be employed for operating two pairs of switch-rails on a railway-crossing independently of each other at will.

In the accompanying drawings, Figure 1 is a top plan view of the railway switch or crossing embodying my improvements. Fig. 2 is a vertical transverse sectional view of the same, taken on the plane indicated by the line *a a* of Fig. 1. Fig. 3 is a sectional view taken on the plane indicated by the line *b b* of Fig. 1, and Fig. 4 is an inverted detail plan view showing the revoluble cam and the connections coacting therewith to independently operate the two pairs of switch-rails.

In the embodiment of my invention here shown the bent rails of the crossing are indicated, respectively, by the reference-numerals 1 2, the said rails being bent in opposite directions, as shown in Fig. 1. Each of the said bent rails is a portion of each of the crossed tracks. One end of the rail is parallel with the rail 1^a of one of the tracks and the opposite end thereof is parallel with the rail 1^b of the other track. The respective ends of the bent rail 2 are similarly disposed with reference to the track-rails 2^a and 2^b. Said rails 1^a 2^a and 1^b 2^b converge in opposite directions and are provided at their converging ends with suitable frogs 3.

It will be observed by reference to Fig. 1 of the drawings that the rails 1^a 1^b are disposed intermediate the bent continuous rails 1 2. A switch-rail 3^a is at the inner end of the rail

2^a and is adapted to be moved into and out of engagement with the inner side of the bent rail 1, the said switch-rail being cut away on one side toward its inner end, as shown. A similar switch-rail 3^b is at the inner end of the rail 2^b and is also adapted to be moved toward and from the inner side of the bent rail 1. Similar switch-rails 4^a 4^b coact with the inner ends of the rails 1^a 1^b, respectively, and are adapted to be moved toward and from the inner side of the bent rail 2. The switch-rails 3^a 4^a are connected together by an operating-rod 5, which is disposed under them and under the rails 1 2 and the plates 6, on which the free ends of said switch-rails operate. The switch-rails 3^b 4^b are also connected together by a similar operating-rod 7. It will be understood from the foregoing that the switch-rails are connected together in pairs by the rods 5 7 and that each pair of switch-rails may be shifted or operated independently of the other.

I will now describe my improved means for operating the pairs of switch-rails. On one side of the track-crossing is a stand 8. In the latter is a vertically-disposed revoluble shaft 9, provided with an arm 10, having a locking member 11, and the switch-stand is provided at its upper end with locking-notches 12, adapted to be respectively engaged by the locking member of the revoluble arm 10 to secure the shaft 9 in any desired position. The said shaft is preferably provided with a signal-board 13, appropriately colored, to indicate the position of the shaft, and hence of the switch-rails. At the lower end of the shaft 9 is a revoluble disk 14, which is fast to the said shaft and is turned thereby. The said disk is a cam-disk and in the construction here shown is provided on its under side with a cam-groove 15, which comprises a segmental section 16, an oppositely-disposed similar section 17, which is of greater radius and is concentric with said section 16, and connecting volute cam-sections 18, the various sections of the cam-groove forming a continuous way in which operate the tappets 19 19^a, which are respectively connected by rods 20 to the rods 5 7, which operate the respective pairs of switch-rails. Each of the tappets is provided with an oscillating detent 21, here shown as a rod

pivoted at its outer end to the stand. These 5 detents maintain the tappets in position for constant engagement with the cam-groove and permit movement of the tappets and of their rods 20 when the cam is turned, as will be understood. On the upper end of the shaft 9 is a spur gear or pinion 22. The latter engages a pair of oppositely-disposed rack-bars 23, each of which is connected to a 10 sliding frame 24, provided with sections of appropriately-colored glass. The said frames operate in a box or housing 25, which is supported above the stand by a suitable standard 25'. The said box or housing is provided 15 at its sides with glazed openings 26, with which the colored sections of glass register when the frames 24 are moved by the turning of the pinion 22 and the rack-bars 23, which coact therewith. It will be understood 20 that the colored glass carried by the sliding frames are signals which indicate the position of the switch-rails to the engineer of an approaching train. At night a light is 25 placed in the housing midway between the sliding frames to illuminate the colored-glass signals and cause them to display appropriately-colored lights. The signals operated by the shaft of the stand may be of any suitable construction within the scope of my invention, and I do not limit myself in this particular.

From the foregoing description, taken in connection with the accompanying drawings, the construction, operation, and advantages 35 of my invention will be readily apparent, it is thought, without requiring a more extended explanation.

Various changes in the form, proportion,

and the minor details of construction may be resorted to without departing from the principle or sacrificing any of the advantages of my invention. 40

Having thus fully described my invention, what I claim as new, and desire to protect by Letters Patent, is— 45

1. A revoluble cam element having a cam-groove comprising oppositely-disposed segmental concentric sections and volute connecting-sections, in combination with movable switch elements, operating-rods for independently moving them and having tappets engaging said cam-grooves, and pivoted detents connected to the said tappets, substantially as described. 50

2. In combination with a movable switch element, a revoluble cam, a tappet actuated thereby and having a pivoted detent, and a connection between the tappet and the movable member, substantially as described. 55

3. A switch-stand having a revoluble shaft 60 and means to turn the same, in combination with a sliding signal element, and operating connections between the latter and said shaft, substantially as described.

4. A switch-stand having a revoluble shaft 65 and means to turn the same, in combination with a sliding signal element having a rack, and a pinion on said shaft engaging said rack, substantially as described.

In testimony whereof I have hereunto set 70 my hand in presence of two subscribing witnesses.

JOSEPH P. HASTY.
